CLAIM

The ornamental design for a media connector module for a tabletop media center, as shown and described.

DESCRIPTION

FIG. 1 shows a top perspective view of a media connector module for a tabletop media center.

FIG. 2 shows a top view of the media connector module for a tabletop media center.

FIG. 3 shows a front view of the media connector module for a tabletop media center.

FIG. 4 shows a rear view of the media connector module for a tabletop media center.

FIG. 5 shows a left side view of the media connector module for a tabletop media center.

FIG. 6 shows a right side view of the media connector module for a tabletop media center; and,

FIG. 7 shows a top perspective view of two side by side media connector modules for a tabletop media center, wherein the tabletop media center shown in broken lines illustrates the environment in which the design is used and forms no part of the claimed design.

The broken lines in the figures depict portions of the media connector module for a tabletop media center that form no part of the claimed design, including an HDMI port in FIGS. 1, 2, and 7, and a DisplayPort in FIG. 7.

1 Claim, 7 Drawing Sheets
